UNITED STATES PATENT OFFICE.

CLAUD B. ELLIOTT AND EMILE E. CLAPPART, OF HEMPSTEAD, TEXAS.

TRAIN-INDICATOR.

1,030,986.

Specification of Letters Patent.

Patented July 2, 1912.

Application filed July 5, 1911. Serial No. 636,893.

To all whom it may concern:

Be it known that we, CLAUD B. ELLIOTT and EMILE E. CLAPPART, citizens of the United States, residing at Hempstead, in the county of Waller and State of Texas, have invented certain new and useful Improvements in Train-Indicators, of which the following is a specification, reference being had therein to the accompanying drawing.

This invention relates to train indicators of the kind in which an apparatus is employed for displaying numbers, names or characters.

The invention has for its object to provide an improved apparatus of this kind which will be simple in construction and effective in operation.

Referring to the accompanying drawings: Figure 1 is a view of the front face of a train indicator constructed in accordance with this invention. Fig. 2 is an enlarged detail plan view in horizontal section of a portion of the apparatus showing the manner of guiding the ribbon in front of an opening. Fig. 3 is an enlarged detail view of a portion of the apparatus shown in vertical section and with parts broken away. Fig. 4 is a detail view in cross section of an operating shaft. Fig. 5 is a detail view showing a portion of one of the rollers and means for engaging said roller with its shaft. Fig. 6 is an enlarged detail end view of the device shown in Fig. 5. Fig. 7 is an enlarged detail view partly in section and broken away of a portion of the driving shaft and its support. Fig. 8 is an enlarged detail view of a portion of the device shown in Fig. 6. Fig. 9 is a view in vertical section showing a pair of rollers and the means for guiding the ribbon in front of an opening.

In carrying out the invention an oblong casing 1 is provided having a number of panels 2 in its front separated by partitions 3 which are located and extend transversely in the casing, each of the panels 2 being formed with an opening 4. Extending lengthwise through the casing 1 adjacent to its top and bottom are shafts 5 having their bearings in the ends of the casing and in the partitions 3, either of said shafts 5 being operated by a detachable handle 5' and in each of the chambers formed by the partitions 3 there are mounted pairs of rollers 6, each of said rollers 6 being loosely mount-

ed on a shaft 5 and connected with each other to rotate in unison by means of a grooved pulley 7 adjacent one end of each of said rollers, and fixed to the shaft 5 an endless belt 8 extending over grooved pulleys 7 on the shafts 5. The rollers are held in spaced position against endwise movement by means of a collar 9 on the shaft 5 between the pulley 7 and the end of the casing 1 or a partition 3. Wound upon each roller 6 of said pairs of rollers is a ribbon 10 which is held adjacent to the opening 4 in each panel 2 of the casing by means of rollers 11, each of which is mounted on a bracket 12 inside of the casing and above and below the opening 4, said ribbon passing over the rollers 11 and being held thereby in a vertical position over the opening 4.

Mounted in a longitudinal socket in one end of each of the rollers 6 is a plug 13 longitudinally movable in said socket and held to turn with the shaft 5 by means of a pin 14 on the shaft 5 projecting through a longitudinal slot 15 in the plug 13, thereby permitting of the longitudinal movement of the plug, and, at the same time causing it to rotate with the shaft 5. The plug is normally held in its outwardly extended position by means of a coil spring 16 located in the socket behind the plug 13, as shown in Fig. 3.

Mounted on one end of the roller 6 is a disk 17 provided adjacent to its periphery with pins 18 with which is adapted to contact an arm 19 projecting from the plug 13 and movable into and out of engagement with the pin 18. In order to move the arm 19 into engagement with one of the pins 18 suitable means is provided, as, for example, the lever arm 20 pivoted to a support 21 on a plate 22 secured to a partition 3, said lever arm having a forked end 23 straddling the shaft 5 and bearing against the end of the plug 13, and the other end of said lever 20 projecting through an opening 23' in the panel 2 and having a handle 24 at its outer end.

By operating the lever 20 the plug 13 may be pushed in against the coil spring 16 until the arm 19 is brought in the path of movement of the pins 18 and is held in such position by securing the lever 20 by any suitable means against the re-action of the coil spring 16. While operating the handle 5' the shaft 5 will be rotated and the arm 19 bearing against a pin 18 will cause the ad-

jacent roller 6 to rotate, thereby winding the ribbon 10 on one roller 6 and unwinding it from the other. Upon releasing the lever 20 the coil spring 16 will automatically throw back the plug 13 to its normal position as shown in Fig. 3, thereby moving the arm 19 out of engagement with a pin 18.

It will be noted that the ribbon can be wound on to one roller and unwound from the other by changing the handle 5' from one of the shafts 5 to the other. As shown each of the ribbons contains a number of figures or other characters, so that by operating separately each lever 20 the numbers presented in the openings of the different panels may be changed by operating one or more of the ribbons by the rotation of a shaft 5.

What we claim is:

20 In an indicator of the kind described, an oblong casing having a horizontal row of sight apertures, driving shafts mounted adjacent to the top and bottom of said casing respectively and extending longitudinally thereof, pairs of rollers mounted on the upper and lower shafts respectively above

and below each sight aperture, a grooved roller adjacent to one end of each of said rollers and fixed to the shaft, an endless belt connecting each pair of grooved rollers, a ribbon with symbols extending past each sight aperture and wound upon said first named rollers, a plug slidably mounted in each of said ribbon-carrying rollers and keyed to said shaft, and having a projecting arm, projections on the end of each ribbon-carrying roller, a spring bearing against said plug to hold its arm out of engagement with the projections on the roller and to automatically return the plug to its normal position, a lever for moving each plug and its arm into engagement with the projections on the roller, and means for operating one of said shafts.

In testimony whereof we hereunto affix our signatures in presence of two witnesses.

CLAUD B. ELLIOTT.
EMILE E. CLAPPART.
